INVENTOR
BY *Victor J. Evans*

ATTORNEY

UNITED STATES PATENT OFFICE.

JOHN ELMER SHEAFFER, OF LOUISVILLE, KENTUCKY.

VALVE.

Application filed August 22, 1925. Serial No. 51,782.

To all whom it may concern:

Be it known that I, JOHN ELMER SHEAFFER, a citizen of the United States, residing at Louisville, in the county of Jefferson and State of Kentucky, have invented new and useful Improvements in Valves, of which the following is a specification.

This invention relates to valves especially designed to be operated from a remote point, 10 an object being to provide a valve for controlling the supply of fuel to a burner, so that the said burner may be lighted and extinguished from a remote point.

The primary object of the invention is to 15 provide a burner valve for use in connection with a water heater, so that a heater located in the basement or other part of a building or dwelling, may be lighted and extinguished from another part of the building or 20 dwelling and time and trouble otherwise required in lighting and extinguishing the burner, will be saved.

With the above and other objects in view, the invention further includes the following 25 novel features and details of construction, to be hereinafter more fully described, illustrated in the accompanying drawings and pointed out in the appended claims.

In the drawings:

30 Figure 1 is a plan view of the valve applied to a burner, the valve being in its closed position.

Figure 2 is a view similar to Figure 1 with the valve open and the burner omitted.

35 Figure 3 is a like view showing the reduced position of the parts preparatory to their return to the closed position illustrated in Figure 1.

Figure 4 is a detail plan view showing the 40 position of the valve stem lever, actuating lever and actuating dog as illustrated in Figure 1.

Figure 5 is a similar view of the valve stem lever and locking dog as illustrated in 45 Figure 2.

Figure 6 is a sectional view taken substantially on the line 6—6 of Figure 7 with the valve open.

Figure 7 is a sectional view taken on the 50 line 7—7 of Figure 6.

Figure 8 is a fragmentary sectional view similar to Figure 6 and showing the valve closed.

55 Figure 9 is a section showing a slightly different form of valve.

Referring to the drawings in detail wherein like characters of reference denote corresponding parts, the reference character 10 indicates the casing of the valve which has extending therefrom a burner nozzle 11, 60 the valve being shown and described for controlling a burner. Various types of burners may be used, one of which is illustrated at B and shown as connected by an elbow E and an air valve V. It is obvious 65 that the valve may be used for various other purposes and it is not the purpose of the present application to limit the invention to the use shown and described.

The valve casing 10 includes an inlet port 70 12 which may be connected to a suitable source of gas supply and is further provided with a tubular extension 13 which carries a pilot burner P, the latter being connected to the extension by a relatively small pipe indicated at 14. At the inner end of the tubular extension 13 there is provided a passage 15 which communicates with the interior of the casing 10, while operating within this casing is a rotary valve member 16. This 80 member is provided with a port or passage 17 by means of which communication may be established between the inlet port 12 and the burner 11, while the passage 15 provides communication between the tubular extension 13, or pilot burner, and the inlet port 12 when the valve member 16 is in closed position. A pilot light will thus be provided so that when the valve member 16 is operated to open the valve, an increased flame 90 will be provided, while a relatively small flame will burn when the valve member is closed. An auxiliary valve 19 is provided in the tubular extension 13 for the purpose of regulating the pilot. This valve member 95 may be adjusted and held in adjusted position by means of a lock nut 20.

The construction covered by the foregoing description may be varied as desired as it illustrates only one of the many uses for 100 which the valve is intended.

Secured upon the reduced squared portion 21 of the valve member 16 is what will be hereinafter termed a valve stem lever, the latter being indicated at 22 and shown 105 in detail in Figure 7 of the drawings. This lever is provided with a squared opening 23 for receiving the squared portion 21 or stem of the valve, so that the valve member and lever 22 will be rigidly associated. The 110

valve stem is also provided with a round or cylindrical portion 21' and a screw 24 and washer 25 serves to rotatably secure an actuating lever 26 upon this portion 21', so that the said actuating lever will be rotatably mounted. Pivotally secured to the lever 26 at 27 is one end of an actuating dog 28. This dog is located within the same plane as the lever 22 and is provided on one edge 10 with a tooth 29 which is adapted to engage in the recess or notch 30 provided in one edge of the lever 22. A spring 31 which has one of its ends connected to the lever 26 and its opposite end connected to the dog 15 28 serves to yieldingly hold the dog in contact with the lever 22. A spring 32 has one of its ends connected to the outer end of the lever 26 and its other end connected to the lever 22, the purpose of the last mentioned 20 spring being later explained.

Pivotally mounted upon the valve casing 10 as shown at 33 is a locking dog 34. This dog is located below the plane of the lever 22 and the dog 28 and is provided with a tooth 35 adapted to engage a lug 36 which extends laterally from the valve stem lever 22 in the path of movement of said tooth. One end of the locking dog 34 has connected thereto one end of a spring 37, the opposite 25 end of which is connected to a pin or stud 38 carried by the casing 10. Extending outwardly from the locking dog 34 near one end thereof is a lug 39 which is located in the path of movement of the actuating dog 30 28 and is adapted to be engaged by the edge 40 of said dog. This edge has extending from its inner end a lug 41 which is adapted to engage the inner edge of the lug 39 during the operation of the valve, as will be 35 later explained. The wire, rod or other member 42 may have one of its ends connected with the outer end of the actuating lever 26 and its other end extended to a 40 convenient point so that a pull upon this wire or rod will move the lever pivotally. The valve member 16 has extending from its inner end a reduced stem 43 which is surrounded by a coiled spring 44 and when the valve is rotated in one direction, this spring 45 50 will be tensioned and will yieldingly resist such movement, and return the valve to its normal position when the latter is released. Another function of the spring 44 is to keep the valve member 16 properly seated.

From the foregoing description and accompanying drawings it will be seen that a pull upon the wire or rod 42 will move the actuating lever pivotally so that the tooth 29 will engage the tooth 30 of the lever 22 and will impart rotary motion to the lever 22 and as this lever is rigid with the valve member 16, the latter will be rotated. During this movement the lug 36 60 which extends laterally from the lever 22

will engage the tooth 35 of the locking dog 34 and will move said dog upon its pivot against the action of the spring 37 and when this lug 36 rides past the tooth 35, the said tooth will drop into position behind the lug 70 as shown in Figure 2 of the drawings and the valve member will then be locked against reverse rotary movement. During this movement, the valve is moved from its normally closed to an open position, the position of the valve being illustrated in Figure 2 of the drawings.

When it is desired to close the valve, the wire or rod 42 is again pulled to impart further rotary movement to the actuating 80 lever 26 in the same direction. This causes the end 40 of the actuating dog 28 to engage the lug 39 of the locking dog and as the free end of the locking dog is held against inward movement by engagement of its end 85 50 with the valve casing, the actuating dog will be moved pivotally outward against the action of its spring 31 and as the locking dog is simultaneously moved upon its pivot against the action of its spring 37, the tooth 90 35 will be disengaged from the tooth 30 and the valve stem lever 22 released. This renders it possible to turn the valve on from a given point and off from another point if desired. Upon the release of the valve 95 stem lever 22, the spring 44 of the valve member will return said member to its closed position, movement in this direction being limited by the engagement of a tooth or extension 46 with the stud 38. This reverse 100 movement of the lever 22, will through the spring 32, pull the actuating lever in the same direction until the tooth or extension 46 of the latter also engages the stud 38. At the same time, the actuating dog will 105 be moved so that its tooth 29 will properly engage the wall of the notch or recess 30 of the lever 22, so that the parts will now be in position to again open the valve when desired.

It will be apparent from an inspection of the drawings that the locations of the screw 19 and pipe 14 may be varied, their positions depending upon the position of the valve when installed. That is, whether the valve is horizontally or vertically arranged.

The invention is susceptible of various changes in its form, proportions and minor details of construction and the right is herein reserved to make such changes as properly fall within the scope of the appended claims.

Having described the invention what is claimed is:—

1. A valve comprising a casing, a rotatable valve member therein, a lever fast upon the stem of the valve, a pivotally mounted actuating lever, an actuating dog carried by said lever, means carried by the dog to en- 130

- gage the valve stem lever to actuate the latter and open the valve when the actuating lever is moved in one direction, means to yieldingly hold the dog and valve stem lever 5 in such engagement, a locking dog, means carried by the locking dog to engage the valve stem lever when the latter is in open position, means carried by the locking dog for engagement by the actuating dog to dis- 10 engage the locking dog from the valve stem lever upon continued movement of the actuating lever, means to automatically return the valve member to closed position when the valve stem lever is released and means 15 to limit pivotal movement of the levers in one direction.
2. A valve comprising a casing, a rotatable valve member therein, a lever fast upon the stem of the valve, a tooth extending 20 from one edge of the lever, a pivotally mounted actuating lever, an actuating dog carried thereby, a tooth extending from one edge of the dog to engage the tooth of the valve stem lever, means to yieldingly hold 25 the actuating dog and valve stem lever in engaged position, whereby movement of the actuating lever in one direction will move the valve member to open position, a locking dog, a tooth carried by the locking dog, 30 for engagement by the actuating dog to disengage the locking dog from the valve stem lever upon continued movement of the actuating lever, means to automatically return the valve member to closed position when 35 the valve stem lever is released and means to limit pivotal movement of the levers in one direction.
3. A valve comprising a casing, a rotatable valve member therein, a lever fast upon the stem of the valve, a tooth extending 40 from one edge of the lever, a pivotally mounted actuating lever, an actuating dog carried thereby, a tooth extending from one edge of the dog to engage the tooth of the valve stem lever, means to yieldingly hold 45 the actuating dog and valve stem lever in engaged position, whereby movement of the actuating lever in one direction will move the valve member to open position, a locking dog, a tooth carried by the locking dog, 50 a lug extending at right angles from the valve stem lever in the path of and engaged by the tooth of the locking dog to hold the valve in open position, means carried by the locking dog to disengage the locking dog from the valve stem lever upon continued movement of the actuating lever, means to automatically return the valve member to closed position when the valve stem lever is released and means 55 to limit pivotal movement of the levers in one direction.
4. The combination with a valve, of an actuating lever, means operated by the lever when the latter is moved in one direction to open the valve, means to hold the valve in open position, means controlled by continued movement of the actuating lever to release the holding means and means to automatically close the valve when 60 said holding means is released.
5. In a gas burner, a controlling valve, a pilot, a valve actuating lever, means operated by the lever when the latter is moved in one direction to open the valve, means to hold the valve in open position, means controlled by continued movement of the actuating lever to release the holding means and means to automatically close the valve when 65 said holding means is released.
6. The combination with a valve, of an actuating lever, means operated by the lever when the latter is moved in one direction to open the valve, means to hold the valve in open position, means controlled by continued movement of the actuating lever to release the holding means and means to automatically close the valve when 70 said holding means is released.

locking dog for engagement by the actuating 55 dog to disengage the locking dog from the valve stem lever upon continued movement of the actuating lever, means to automatically return the valve member to closed position when the valve stem lever is released and means to limit pivotal movement of the levers in one direction.

4. A valve comprising a casing, a rotatable valve member therein, a lever fast upon the stem of the valve, a tooth extending 65 from one edge of the lever, a pivotally mounted actuating lever, an actuating dog carried thereby, a tooth extending from one edge of the dog to engage the tooth of the valve stem lever, means to yieldingly hold 70 the actuating dog and valve stem lever in engaged position, whereby movement of the actuating lever in one direction will move the valve member to open position, a locking dog, a tooth carried by the locking dog, 75 a lug extending at right angles from the valve stem lever in the path of and engaged by the tooth of the locking dog to hold the valve in open position, a lug carried by the locking dog in the path of movement of the 80 actuating dog, whereby continued movement of the actuating lever will release the valve stem lever, means to automatically return the valve member to closed position when the valve stem lever is released and means 85 to limit pivotal movement of the levers in one direction.

5. In a gas burner, a controlling valve, a pilot, a valve actuating lever, means operated by the lever when the latter is moved 90 in one direction to open the valve, means to hold the valve in open position, means controlled by continued movement of the actuating lever to release the holding means and means to automatically close the valve when 95 said holding means is released.

6. The combination with a valve, of an actuating lever, means operated by the lever when the latter is moved in one direction to open the valve, means to hold the valve in 100 open position, means controlled by continued movement of the actuating lever to release the holding means and means to automatically close the valve when said holding means is released.

In testimony whereof I affix my signature.

JOHN ELMER SHEAFFER.
